UNITED STATES PATENT OFFICE

161,261

COMBINED SCRAPER AND COIN HOLDER

Kenneth R. Hagen, Paris, Ill., assignor to U. O.
Colson Company, Paris, Ill., a corporation of Illinois

Application May 15, 1950, Serial No. 9,945

Term of patent 14 years

(Cl. D87—3)

To all whom it may concern:

Be it known that I, Kenneth R. Hagen, a citizen of the United States, residing at Paris, in the county of Edgar and State of Illinois, have invented a new, original, and ornamental Design for a Combined Scraper and Coin Holder, of which the following is a specification, reference being had to the accompanying drawing, forming part thereof.

I claim:

The ornamental design for a combined scraper and coin holder, as shown.

KENNETH R. HAGEN.
